WINDOW SHADE

Samuel J. Johnson, Cincinnati, Ohio, assignor to
Clopay Corporation, Cincinnati, Ohio, a corpora-
tion of Maryland

Application December 19, 1934, Serial No. 758,289

2 Claims. (Cl. 156—10)

This invention relates to improvements in window shades, particularly that type of shade which is operated on a roller.

The present improvement is primarily concerned with and directed to paper window shades. It is natural of course that paper is not as strong as cloth and its edges are more apt to tear. Accordingly, it is an object of the present invention to provide an improved paper window shade which incorporates an edge construction which considerably reinforces and strengthens the edges, whereby there is less opportunity for tearing and splitting, and whereby there is less tendency for the shade to stretch, the occurrence of which would cause it to buckle and hang unevenly.

Other objects and further advantages will be more fully apparent from a description of the accompanying drawing, in which:

20 Figure 1 is a general view showing the improved window shade mounted in relation to a window.

Figure 2 is a fragmentary perspective view of the shade and roller, detailing the edge construction of this invention.

Referring to the drawing, the roller is indicated at 5 and the sheet of paper constituting the shade at 6. The length of paper has a hem 7 formed at its lower end, in which hem a stiffening cross piece 8 is disposed. This cross piece provides definite body to the lower end of the shade and provides a rigid element to which the manipulating means may be efficiently attached.

35 The conventional manipulating means is disclosed consisting of a cord 9 attached centrally of the lower edge of the shade through the stiffening cross piece and carrying a ring 10 at its lower end. The shade is attached to the roller 5, the roller being mounted in brackets 11 and 12 fixed to the upper part of the window frame 13.

The roller includes trunnions 14 and 15 mounted in the respective brackets. The shade roller disclosed may be of any conventional character, and therefore includes a rotating trunnion 15 rotatably fixed in the bracket 12 and a non-

rotative trunnion fixture 14 mounted against rotation in the other bracket 11 and carrying a spring and suitable ratchet mechanism (not shown) in conjunction with the roller, whereby as the shade is pulled down the spring is wound up and return tension placed thereon for causing the shade to automatically raise when the ratchet is released.

The improvement may be advantageously applied to a crepe paper window shade of the character now in commercial use. Although the crepe paper used in the fabrication of these shades has its grain disposed in a particular manner, that is, transversely or at right angles with the roller as disclosed in this applicant's Patent No. 1,807,533, 15 issued May 26, 1931, and minute creasing or embossing is applied to the paper transversely to the grain, there still may be a tendency for the edge of the paper to curl or to split as the user exerts pressure thereon for the purpose of lowering the shade. To lessen the possibility of tearing occurring at the edges, the longitudinal side edges are reinforced by an indentation or single corrugation 16 immediately adjacent to the edge. It has been found that these indentations 20 applied along the edges as they are tend to lessen buckling, curling and tearing, also having the effect of stiffening the edge and in this way tending to keep it straight.

Having described my invention, I claim: 30

1. As a new article of manufacture, a window shade, comprising a length of paper having at one end thereof a manipulating means and having its other end adapted to be attached to a roller, said length of paper having a corrugation 35 extending along each of its longitudinal side edges for increased strength and stiffness.

2. As a new article of manufacture, a window shade, comprising, a length of crepe paper including a manipulating means at one end and having 40 its other end adapted to be attached to a roller, said length of paper having each of its longitudinal side edge margins strengthened by a corrugation extending along the edge immediately adjacent thereto. 45

SAMUEL J. JOHNSON.
